UNITED STATES PATENT OFFICE.

STANLEY W. HAYES, OF RICHMOND, INDIANA, ASSIGNOR TO HAYES TRACK APPLI-
ANCE COMPANY, OF RICHMOND, INDIANA, A CORPORATION OF INDIANA.

DERAIL.

1,420,425.

Specification of Letters Patent. Patented June 20, 1922.

Application filed January 23, 1919, Serial No. 272,670. Renewed November 28, 1921. Serial No. 518,431.

To all whom it may concern:

Be it known that I, STANLEY W. HAYES, United States citizen, residing in Richmond, county of Wayne, Indiana, have invented 5 the following described Improvements in Derails.

The invention provides a light weight derail that can be conveniently thrown either by hand or pipe-line and consists in the 10 structure of the derailing member and its relation to the guide box or base and in the organization therein of a hand operated power-multiplying mechanism as hereinafter explained and more particularly pointed out 15 in the claims.

In the drawings—

Fig. 1 is a side elevation of the derail on the rail.

Fig. 2 is a partly sectional elevation of 20 the same derail partly withdrawn.

Fig. 3 is a side elevation of the rail.

Fig. 4 a top plan.

Fig. 5 a rear view partly in section showing the rear bearing.

25 The base member comprises two upstanding side wall portions 1, united by lower cross wall portions 2 and 3 the latter provided with exterior spike flanges 4 adapted to be spiked to two adjacent ties. The base 30 is open, having no upper crossbar or roof member, and the interior is occupied by the derailing member, which latter is mounted on forward and rear bearings therein so that it advances horizontally to the rail and 35 withdraws therefrom, first with an upward and then with a downward movement, its withdrawn or open position being depressed at one side of the rail. The derailing member comprises the body or supporting part 40 5 and the derail block 6 and is cast in one piece and hollow on its under side for lightness and to provide accommodation and shelter to the rear bearing and subjacent parts. The forward bearing is provided by 45

50 two studs 7 projecting laterally from the lower end of the shoulder structure 8 at the forward end of the body part of the derailing member, near the derail block, and sliding in grooves 9 formed in the inner 55 faces of the sides 1. These grooves are curved to give the derail block the up-and-over movement above mentioned and their engagement with the studs also serves to hold the derailing member against upward displacement. This particular form of for-

ward bearing is preferred for the case in hand but may be substituted by other arrangements producing the same or equivalent effect. The rear bearing is formed by a central longitudinal web or rib 10 depending from the rear of the movable member and sliding by its lower curved edge upon a rounded surface 11 formed on the rear cross wall 3. The said rib is confined to such surface, on the one hand, by the 60 base lug 12 and on the other, by the undercut base lug 13, the structure of which overlaps a side rail 14 on the rib 10 to keep it from upward displacement. Such rear rib bearing is central between the vertical planes 65 of the two forward bearing studs 7, and thereby prevents cramping of the member in the base, while the vertical curvature of the rib contributes a desirable additional vertical component to the motion of the 70 derailing member, designed to keep the operating lug 15, and hence the pipe-line rod 16 attached thereto, at a substantially constant level in all positions, and otherwise to facilitate the movement of the member as 75 will be apparent. The said operating lug 15 is cast on the rear of the body 5, and extends downwardly to a point below the level of the cross walls 2 and 3 so that the pipe-line when used, may run as usual beneath 80 the rail. The derail shown may also be provided with a duplicate attachment lug 17 (Figs. 4 and 5) for connection to a target staff or other track appliance or connection 85 as desired.

90 For direct hand operation, the derail is provided with a power-multiple device in the form of a hand lever 18 fulcrumed on a lower stationary support, for instance upon the lug 19 projecting from the forward side of the cross wall 3 and having a bearing on the derailing member preferably at a central point thereof and by means of this lever the heaviest sizes of derails may be thrown with little effort. The preferred 95 form of operating mechanism is a lever of the second class as shown, passing through a hole 20, in the forward center of the body 5, and curved in a fore and aft direction so that it can occupy a substantially horizontal position when the derail is off the rail. Derails are commonly placed between the rails of the track and the lever 18 is therefore in this manner arranged to be out 100 of the way of passing rolling stock when 105 110

the derail is open, while when the derail is closed the hand lever is upstanding and may serve as a signal device depending on its length. The curvature of the lever is 5 preferably formed in that part of its length which engages the bearing represented by the rounded edges of the hole 20, and thereby it acts with a camming effect on the derailing member, further multiplying the 10 power effect thereon which is particularly useful in raising it from its depressed position against obstruction by frost or other cause. Such camming effect is supplementary to the primary function of the lever 15 and due to its curvature but the invention contemplates the use of any power-multiplying mechanism as a means of enabling large-sized and heavy derails to be directly thrown by hand by an operator standing at 20 the derail. Such mechanism may however be omitted when the derail is to be operated solely by the pipe-line, but the structure is preferably manufactured with the fulcrum lug 19 and with the other lugs 15 and 25 17 upon it in any case, so that it may be sold for use either way.

The two main parts of the derail are assembled by placing the derailing member in the base in a position slightly forward 30 of that indicated in Fig. 1, and before the base is spiked to the ties and then introducing the rib 10 and studs 7 into their respective bearings and sliding them rearwardly therein. When the base is thereafter secured to the ties the obstruction represented 35 by the adjacent rail-head confines the derailing member in its bearings as will be obvious. The rear end of the side wall portion is provided with a perforated ear 23 and the derailing member is formed with 40 two abutment surfaces 21 and 22 so that a padlock hasp inserted through the ear will coact with either abutment to lock the member either opened or closed.

45 It should be noted that the studs 7 are located at the extreme forward end of the base and are therefore close to the rail when the derail is open, in which position their function of holding the block against 50 kicking up on wheel impacts is most effective, being thereby freed from much of the leverage effect that has heretofore been present in derails having the sliding movement above described. This result is obtained by 55 forming the said studs 7 at the lower ends of the shoulder structure 8 directly under the derail block 6 instead of on the sides of the body part 5 of the derailing member, and it is manifestly independent of the 60 specific manner of sliding support.

Claims:

1. A derail comprising a base, a derailing member mounted thereon on forward and rear bearings, the rear bearing formed 65 by a central rib depending from the said

member and sliding on and confined to a central bearing surface on said base.

2. A derail comprising an open base, a derailing member mounted thereon on a forward bearing imparting up-and-over movement thereto, and on a rear bearing comprising a central rib depending from said member and sliding on and confined to a bearing surface on the base. 70

3. A derail comprising an open base member, a derailing member mounted therein on forward and rear bearings, the rear bearing comprising a rib on one of said members sliding on a bearing surface in an undercut recess formed in the other member 80 and held thereto by the undercut formation. 75

4. A derail comprising a base and a derailing member having a depending web or rib with a curved lower edge sliding on a bearing surface formed on the base. 85

5. A derail comprising a base, a derailing member having a central depending web or rib supported by a bearing on the base and a rail on the rib adapted to confine the same 90 to said bearing.

6. A derail comprising a base and derailing member, a forward bearing therefor adapted to impart an up-and-over movement to said member and a rear bearing 95 constituted by a rib depending from said member and having a curved lower edge adapted to slide on the base.

7. A derail comprising in combination, a base, a derailing member movable therein 100 toward and from the rail and a handle member mounted on the derail, having a power-multiplying connection with said member for moving the same, on the base, toward and from the rail. 105

8. A derail comprising a base, a derailing member movable therein, and a hand lever of the second class fulcrumed on the base and adapted to move said member toward and from the rail. 110

9. A derail comprising a base, and a derailing member adapted to occupy a depressed position at the side of the rail, combined with a hand lever by which the member may be moved, said lever being organized with said base and member to move to a substantially horizontal position when moving the member to said depressed position. 115

10. A derail comprising a base, adapted 120 to be mounted between the rails and a derailing member movable thereon combined with a hand lever incorporated in the derail and adapted to operate the derail by movement from an upright to a substantially 125 horizontal position.

11. A derail comprising a base and a derailing member moving therein toward and from the rail, the rear bearing being of the sliding type combined with a hand lever for 130

moving the derailing member, said lever having engagement with the member at a substantially central point thereof.

12. A derail comprising a base, a derailing member sliding therein toward and from the rail and an operating lever fulcrumed on the base and extending through an aperture in the derailing member.

13. A derail comprising a base, a derailing member movable thereon toward and from the rail, and a lever having a curved surface in engagement with said member.

14. A derail comprising a base, a derailing member movable thereon toward and from the rail upon forward and rear bearings, the rear bearing being formed to impart a vertical component to said movement and an operating lever engaged with said member.

15. A derail comprising a base and a derailing member and a curved lever engaged therewith to move said member, the curvature of said lever serving to place it in a substantially horizontal position when the derail is off the rail.

16. A derail of the sliding type comprising a base and derailing member and a lever fulcrumed on the base and adapted to operate the member.

17. A derail comprising a base and derailing member and a lever fulcrumed on the base independently of the support of said member thereon and adapted to move the latter toward and from the rail.

In testimony whereof, I have signed this 35 specification.

STANLEY W. HAYES.
